Primary Examiner—Bernard Ansher*Assistant Examiner*—Richelle Shelton*Attorney, Agent, or Firm*—Wood, Herron & Evans[57] CLAIM

The ornamental design for a beverage bottle transporting crate, as shown and described.

DESCRIPTION

FIG. 1 is a perspective view of a beverage transporting bottle crate showing my new design;

FIG. 2 is a top plan view thereof;

FIG. 3 is a side elevational view thereof, the opposite side being a mirror image thereof;

FIG. 4 is an end elevational view thereof, the opposite end being a mirror image thereof;

FIG. 5 is a bottom plan view thereof; and,

FIG. 6 is a cross sectional view taken on the direction of the arrows of line 6—6 of FIG. 2.

FIG. 1

FIG. 2

FIG. 3

FIG. 4

FIG. 6

FIG. 5

UNITED STATES PATENT AND TRADEMARK OFFICE
CERTIFICATE OF CORRECTION

PATENT NO. : Des. 351,731

DATED : October 25, 1994

INVENTOR(S) : Rafael T. Bustos and Joseph M. Battaglia

It is certified that error appears in the above-identified patent and that said Letters Patent is hereby corrected as shown below:

On the title page,

In the description of the drawings, the sentence describing Fig. 1 should read as follows:

---Fig. 1 is a perspective view of a beverage bottle transporting crate showing my new design;---

Signed and Sealed this

Fourteenth Day of March, 1995

Attest:

BRUCE LEHMAN
